UNITED STATES PATENT OFFICE.

SAMUEL I. EPSTEIN, OF BROOKLYN, NEW YORK.

DESIGN FOR A CANDY UNIT.

Application filed March 7, 1925. Serial No. 12,626. Term of patent 7 years.

To all whom it may concern:

Be it known that I, SAMUEL I. EPSTEIN, a citizen of the United States, residing at Brooklyn, in the county of Kings and State of New York, have invented a new, original, and ornamental Design for a Candy Unit, as shown in the accompanying drawing and described in the following specification.

The drawing is a perspective view of a candy unit constituting my new design.

I claim:

The ornamental design for a candy unit as shown.

SAMUEL I. EPSTEIN.
